UNITED STATES PATENT OFFICE.

HERMAN HESS, OF BALTIMORE, MARYLAND.

DESIGN FOR A HEEL.

55,127.

Specification for Design.

Patented May 11, 1920.

Application filed January 27, 1920. Serial No. 354,482. Term of patent 14 years.

To all whom it may concern:

Be it known that I, HERMAN HESS, a citizen of Poland, residing at 2106 Wilkins avenue, Baltimore, in the county of Baltimore, State of Maryland, have invented a new, original, and ornamental Design for a Heel, of which the following is a specification, reference being had to the accompanying drawing, forming part thereof.

In the drawing the figure is a view in perspective showing my invention.

I claim:

The ornamental design for a heel, as shown.

HERMAN HESS.
